UNITED STATES PATENT OFFICE

AUGUSTIN EMMANUEL JANSON DE COUËT, OF BROMLEY, ENGLAND

CONTAINER FOR SEMIQUID MATERIALS

Application filed January 7, 1929, Serial No. 330,831, and in Great Britain January 19, 1928.

The object of the present invention is to provide an improved container for face creams, ointments and like semi-liquid materials, which is clean in use and prevents 5 waste.

The invention relates to that type of container for a semi-liquid material which is made in two parts screwing with relation to each other, and thereby forcing the semi-10 liquid material out through an aperture in one of the parts. Such containers are usually provided with a lid or cover.

According to the present invention I employ a plunger which is adapted to screw 15 down into the box and the said plunger is provided with a comparatively small aperture therethrough so that when it is screwed with relation to the body of the box the semi-liquid material contained within the body will be forced out through the aperture in the plunger into a cup in the outer end of said plunger. The plunger is covered by a detachable lid which preferably fits by friction 20 down on to a shoulder upon the body of the box in known manner. The plunger is preferably formed with a flange at its outer end which flange is integral with the plunger and it may be knurled to enable the plunger to be more readily rotated. This knurling forms 25 short radial projections or finger grips arranged around the outer periphery of said cup.

The invention is illustrated in the accompanying drawings in which:

Fig. 1 is a side elevation of the complete article with the lid or cover detached from the body of the box.

Fig. 2 is a section on the line 2—2 of Fig. 1.

Fig. 3 is a plan of the plunger and body of 40 the box.

Fig. 4 is a section similar to part of Fig. 2 but showing a modification.

Fig. 5 is a section on the line 5—5 of Fig. 6 showing a second modification.

Fig. 6 is a plan of the plunger and body of the box shown in Fig. 5.

a is the body of the box which is screw threaded in its interior at *b* and is formed with a shoulder *c* to receive the cover *d* of the 50 box which fits by friction on the said body.

e is a plunger made of solid material which is screw threaded on its exterior to fit the screw thread *b* within the body of the box. The plunger *e* has an aperture therethrough and, as shown in Fig. 2, the lower part of the 55 aperture at *f* is of larger section than the upper part of the aperture at *g*, through which the semi-liquid material is forced. The said aperture leads into a cup *g'* formed in the upper end of the plunger *e*. The 60 plunger *e*, as shown in Figures 1, 2 and 4, has a flange *h* at its outer end which is knurled as seen in Figure 1 to form suitable finger grips arranged around the outer periphery of said cup. The flange *h* is formed integral 65 with the plunger *e*.

In the modification shown in Fig. 4 the plunger *e* has a small aperture *g* from end to end thereof which leads into a cup *g'* in the end of the plunger. If the plunger is made 70 sufficiently long it is possible to force out the whole of the contents of the body *a* of the box. When the body *a* of the box is refilled any semi-liquid material remaining in the aperture through the plunger *e* will be first 75 expelled for use, thus ensuring always a fresh supply of the material for toilet purposes.

In the modification shown in Figs. 5 and 6 the body *a* of the box is flatter than shown in Figs. 1, 2 and 4 and the plunger *e* is conical 80 and is provided with wings *i*, *i* on its upper surface which enable it to be readily rotated. The wings *i*, *i* are formed integral with the plunger *e* and the aperture *g* leads into a cup 85 *g'* located between the inner ends of the wings *i*, *i*.

What I claim as my invention is:—

1. A container for semi-liquid materials, said container comprising a hollow cylindrical receptacle open at its upper end and having its inner cylindrical wall threaded from top to bottom, a plunger threaded into the inner cylindrical wall of said hollow receptacle, said plunger being provided with an axial aperture extending outwardly from an inwardly-presented wall thereof, and with a cup in an outwardly-presented wall thereof into which the outer end of said aperture discharges, and finger grips carried by said 100

plunger, said finger grips being arranged around the outer periphery of said cup.

2. A container for semi-liquid materials, said container comprising a hollow cylindrical receptacle open at its upper end and having its inner cylindrical wall threaded from top to bottom, a conical disk-like plunger having its apex presented upwardly and with its peripheral edge threaded into the inner cylindrical wall of said hollow receptacle, said conical disk-like plunger being provided with an axial aperture extending outwardly from the apex of the inner conical wall of said disk-like plunger and with a cup at the outer end of said aperture, and radial wings or finger grips extending outwardly from the outer periphery of said cup.

In witness whereof I have hereunto set my hand.
